UNITED STATES PATENT OFFICE.

ADRIEN PHILIPPE, OF GENEVA, SWITZERLAND, ASSIGNOR TO PATEK,
PHILIPPE & CO., OF SAME PLACE.

DESIGN FOR A WATCH-BRIDGE.

SPECIFICATION forming part of Design No. 20,483, dated January 13, 1891.

Application filed September 19, 1890. Serial No. 365,550. Term of patent 14 years.

To all whom it may concern:

Be it known that I, ADRIEN PHILIPPE, a citizen of the Republic of France, residing at Geneva, Switzerland, have invented a new and original Design for Watch-Bridges for Watch-Movements, of which the following is a full, clear, and exact specification, reference being made to the accompanying drawing, in which my said design is illustrated on an enlarged scale.

The leading feature of this design is the ornamental shape of the plate G and bridge B in connection with the other bridges of the watch-movement. The bridge C is a compound curve, as shown, and the sides of the bridge B are parallel, and the end of the same next the side of the bridge C is an arc of a circle parallel to the curved side of said bridge C. The plate G is between the bridges

B C, and its outer edge is an arc of a circle. 20 The edge next to the bridge C is concave and parallel to the convex edge of the bridge C. The bridge or cock F is near the end of the bridge C, and the curved bridges D E are of ordinary shape, but they compose part of the 25 entire design of the watch-bridges.

I claim—

In the design for the bridges of a watch-movement, the design of the bridges or plates B, G, and C, as represented. 30

In testimony whereof I have signed my name to this specification in the presence of two subscribing witnesses.

ADRIEN PHILIPPE. [L. S.]
